LIFEBOAT LAUNCHING DEVICE

Jean Badovici, Paris, France

Application May 2, 1934, Serial No. 723,563
In France May 17, 1933

3 Claims. (Cl. 114—0.5)

The lifeboat forming the subject-matter of the present invention is designed for use in saving the crew and passengers from sinking war-ships and merchant ships. This lifeboat, which forms in effect a part of the ship of which it takes the shape, is arranged on an inclined cradle placed in a recess provided at the stern of the ship, with the level of the rear upper deck portion of the ship corresponding to the level of the deck of the lifeboat. The cradle carrying the lifeboat is maintained in a vertical position, whatever may be the list the ship may have, owing to the arrangement, under the cradle, of a roller device capable of moving to the right or to the left of the longitudinal axis of the ship on curvilinear rails, rigid with the wall of said recess.

A form of carrying the invention into practice is illustrated in the accompanying drawings, in which:

- 20 Fig. 1 is an elevation of the lifeboat afloat.
 Fig. 2 is a horizontal section partly in plan of the same.
 Fig. 3 is a vertical longitudinal section of the lifeboat.
 25 Fig. 4 is a cross section made according to line 4—4 of Fig. 2.
 Fig. 5 is a longitudinal horizontal section made according to line 5—5 of Fig. 4.
 Fig. 6 is a transverse section of the cradle on the line 6—6 of Fig. 7.
 Fig. 7 is a plan view of the cradle.
 Fig. 8 is a perspective view, partly in section, of the cradle.
 30 Fig. 9 is a side elevation of the ship indicated diagrammatically and showing the lifeboat mounted at the rear end thereof.
 Fig. 10 is a plan view of the same.
 Fig. 11 is a rear view of the ship on an even keel showing the lifeboat mounted on the cradle.
 40 Fig. 12 is a view similar to Fig. 11, the ship being shown on an uneven keel with the lifeboat, by reason of the cradle, remaining on an even keel with respect to the water, the cross lines of Fig. 12 illustrating the horizontal and vertical axial plane of the ship when on an even keel.

The lifeboat 1 includes a double hull 2 divided into compartments 3. The latter, located below the water level line, contain compressed air, so as to reduce as much as possible the consequences of a leak. Moreover, this hull 2 is provided with watertight bulkheads 4 which form compartments also capable of receiving compressed air.

The walls of the hull 2 are thicker at the level of the water level line and they are stronger under 55 the essential parts of the lifeboat, for instance

under the fuel and store-rooms 5 and under the engine room 6.

The various sheet metal plates and other frame members used for the construction of the hull are connected by autogenous or electric welding. 5

The deck 7 hermetically closing the lifeboat, carries the superstructure of the latter, comprising the commanding officer's cabin with a bridge 8, formed by a hood 9, provided with low windows 10 and having fresh air shafts and shafts for 10 the evacuation of foul air.

Under the deck of the commander's cabin 8 are arranged watertight doors 11, opening on a deck portion 12 situated nearly at the sea level. This deck portion 12 is divided into passages 13 by 15 chains 14 or other hand rails supported by fixed or removable posts 15.

The various doors 11 open on an entrance 16 terminating in a central passage 17, the floor of which is inclined in order that staircase steps may 20 be dispensed with. The passage 17 gives access to a central distributing cabin 18 communicating with large circular and side cabins 19, 20. Along the passage 17 are provided the infirmary 21 and the guard's room 22. 25

An anchor room 23 is provided in the bow 24 of the lifeboat.

To the right and to the left of the side planking are arranged swinging booms 25 adapted, when they are lowered, to assist in the rescue, by means 30 of ropes and rope ladders 26, of persons who have fallen overboard.

The commanding officer's post is connected to the deck 27 of the engine room 6 by staircases and inclines. The engine room 6 is surrounded 35 by cabins 29, similar to the cabins 19, 20. An electric kitchen 30 is provided under the central cabin 18.

The internal combustion engines actuating the generators of electricity are supplied with fuel 40 contained in a compartment 31, located under the floor of the deck portion 12, which, owing to its enfolding shape, protects the screw propellers 32, actuated by electric motors 33.

In the compartment located under the deck 21 45 are arranged electric accumulators. The room 34 contains a gyroscopic apparatus 35 for preventing rolling, such being maintained in motion by a suitable electric motor. Cold rooms and the steward's room are located under the kitchen 30. 50

The lifeboat above described forms an integrant part of the ship *a* provided with the same, and is housed in a recess *b* formed at the stern and in the longitudinal axis of the ship.

When the said lifeboat 1 is in its recess *b*, the 55

hull 2 of the lifeboat completes and exactly conforms to the rear shape c of the stern of said ship.

The lifeboat is supported in its recess b by a cradle, the telescopic longitudinal members 36 of which serve as a slipway for the hull 2, and are secured on cross members 37, provided with rollers 38, angularly movable in a curvilinear track 39 secured on the walls of the recess b.

This device provides for holding the lifeboat in a normal position, since the cradle carrying it can move angularly to the right and to the left of the vertical axis of the ship.

For launching a lifeboat according to the present invention, it is only necessary to release it from all the mooring ropes attaching it to the ship so that it can immediately slide on the longitudinal members 36, the telescopic parts terminating the fixed parts of the cradle sliding on the said longitudinal members 36 in order that the said lifeboat should be supported until it floats. If the ship has a list when the lifeboat is launched, as indicated in Fig. 12, the cradle will nevertheless maintain an upright position as shown.

For hoisting the lifeboat on its cradle, the longitudinal members 36 are caused to enter the water in order to form an incline support on which the lifeboat may be hoisted by means, on the one hand, of a capstan and, on the other hand, by rollers 41 provided with teeth which engage with the teeth of racks 40 secured along the longitudinal members 36. These rollers can be actuated by the engine of the lifeboat.

The means for hoisting the lifeboat is indicated more particularly in Fig. 9 and shows a capstan 45 mounted on the ship and a second capstan 46 mounted on the lifeboat. A cable 47 goes from one capstan to the other. By winding or unwinding the cable 47 on either of the capstans, the lifeboat may be hoisted or lowered as desired.

The means for rotating the toothed rollers 41 is illustrated in Fig. 1 wherein the propeller shaft 32 is lengthened and carries a screw 48 which acts upon a worm wheel 49. A worm pinion 50 is keyed on the propeller shaft and transmits the rotation of such shaft to the toothed roller 41, designed to engage the racks 40 on the cradle.

Once it is housed in its recess, the lifeboat is held stationary by any suitable means, by screw jacks for instance.

During normal running of the ship carrying a lifeboat according to the present invention, the latter is reserved for the crew who may occupy the cabins 19, 20 and 29, which may be provided with hammocks or other sleeping accommodations. Moreover, the lifeboat may be used to contain the food reserves of the ship, so as to be quite ready in case of emergency.

It will be provided with sending and receiving wireless sets, with distress vertical searchlights, as well as with all accessories necessary for the rescue of the passengers. It can be adapted to existing ships by modifying the sterns of the latter in order to form the recess necessary for receiving the said lifeboat.

For large liners, the importance of the lifeboat may be supplemented by other smaller lifeboats housed in the longitudinal flanks of the ship.

I claim:

1. A ship comprising a main hull having a recess formed above the water line, at the stern and in the longitudinal axis of the ship, said recess having a bottom surface sloping to the rear and terminating substantially at the water line, said bottom surface being concave in cross-section, transverse curvilinear tracks on said bottom surface, a cradle supported on said tracks and comprising telescopic extensible longitudinal members sloping to the rear and curved cross members, rollers mounted on said cross members and rolling on said tracks, and a lifeboat detachably secured in said recess and slidably supported on said telescopic extensible longitudinal members.

2. A ship comprising a main hull having a recess formed above the water line, at the stern and in the longitudinal axis of the ship, said recess having a bottom surface sloping to the rear and terminating substantially at the water line, said bottom surface being concave in cross-section, transverse curvilinear tracks on said bottom surface, a cradle supported on said tracks and comprising longitudinal members sloping to the rear and curved cross members, rollers mounted on said cross members and rolling on said tracks, a lifeboat detachably secured in said recess and slidably supported on said longitudinal members, and means for hoisting said lifeboat along said longitudinal members.

3. A ship comprising a main hull having a recess formed above the water line, at the stern and in the longitudinal axis of the ship, said recess having a bottom surface sloping to the rear and terminating substantially at the water line, said bottom surface being concave in cross-section, transverse curvilinear tracks on said bottom surface, a cradle supported on said tracks and comprising longitudinal members sloping to the rear and curved cross members, rollers mounted on said cross members and rolling on said tracks, a lifeboat detachably secured in said recess and slidably supported on said longitudinal members, racks mounted on said longitudinal members, toothed rollers mounted on said lifeboat and adapted to engage said racks, and means for rotating said toothed rollers.

JEAN BADOVICI.
